Herbert Töpfer and Erich Ehricke, Berlin-Siemensstadt, Germany, assignors to Fides Gesellschaft für die Verwaltung und Verwertung von gewerblichen Schutzrechten mit beschränkter Haftung, Berlin, Germany, a corporation of Germany

Application March 30, 1939, Serial No. 264,878
In Germany April 12, 1938

2 Claims. (Cl. 179—9)

The invention relates to a circuit arrangement for two conductor two-way junction lines in automatic telephone systems. On the simultaneous seizing of such a junction line from both directions it can happen that one of the two subscribers connected at opposite ends releases the signal for the conversation to begin, e. g. by operating his dial or hanging up his receiver so that the subscriber at the opposite end is charged with a fee in error.

Arrangements for two-way junction lines are already known which by giving preference to a connection in one direction prevent the simultaneous seizing from both directions by allowing the line to be seized from the other direction but disconnecting it so quickly that the above mistake cannot occur. Since however, the known arrangements for bringing about the preferred seizing of the junction line in a particular direction usually have the disadvantage that the seizing operation is prolonged and thus the free selecting period of the selector seizing the junction line is shortened, the invention proceeds by another method in order to avoid the danger of an erroneous metering of a conversation. This method according to the invention, consists in using for the switching operations to be transmitted back over the junction line in the course of setting up a connection, in particular the signal for the beginning of the conversation, only impulses of such a type, (e. g. different frequency, type of current, voltage) or duration are used that they cannot be simulated by the impulses serving to transmit the switching operations in the forward direction.

Fig. 1 shows diagrammatically an arrangement for two-way traffic.

Fig. 2 shows one embodiment of the invention in which different frequencies of current are used for forward and backward signalling.

Fig. 3 shows another embodiment of the invention in which currents of the same frequency, but of different lengths, are used.

Fig. 4 shows another embodiment of the invention in which inductive currents are used for signalling in one direction, while alternating current is used for signals in the other direction.

In the arrangement according to Fig. 1 the two exchanges A and B are connected with one another by means of the junction line VL. If the subscriber Ta1 of the exchange A wishes to make a connection with the subscriber Tb2 of the exchange B then after the subscriber Ta1 has taken up his receiver his pre-selector VWa hunts

5 for a free first group selector 1GWa. The group selector set by means of the first impulse train hunts for a free junction line VL. The junction line VL is associated in the exchange A with a two-way repeater UA and in the exchange B with a similar repeater UB. The usual two-conductor junction line VL can be adapted for direct current operation, alternating current operation or inductive direct current impulse 10 transmission. After the seizing of the repeater UA by means of the first group selector 1GWa the seizing over the junction line VL to the repeater UB and from this to the second group selector 2GWb of the exchange B connected to 15 the repeater is carried out. The group selector 2GWb is set by the next impulse transmission from the calling subscriber on a free final selector LWb and this is set by the last impulse train on the required subscriber Tb2.

20 A connection in the opposite direction between the subscriber Tb1 of the exchange B as calling party and the subscriber Ta2 of the exchange A as called party extends over pre-selector VWb, first group selector 1GWb, repeater UB, junction line VL, repeater UA, second group selector 2GWa, final selector LWa, subscriber Ta2.

25 The Figs. 2, 3 and 4 show three different embodiments of the invention in connection with a number of circuits of the repeaters UA and UB at the ends of the junction lines. The circuit details of the repeater are only shown in so far as is necessary for the understanding of the invention. The repeaters UA and UB are completely similar to one another in their circuit 30 connections. Since they serve for outgoing as well as for incoming traffic, switch means are arranged in each repeater in the part of the line branch incoming to the group selector and in the part of the branch line extending to a group selector as indicated by a horizontal dotted separating line.

35 Fig. 2 shows as the first embodiment of the invention an arrangement in which the forwardly directed switching operations, i. e. extending in the direction from the calling to the called parties over the guarded junction line are all transmitted with a particular frequency e. g. 50 cycles, while the switching operations to be transmitted backwards, in particular the signal for the metering operation is transmitted with another frequency, e. g. 100 cycles.

40 In detail the method of working of the arrangement of Fig. 2 is as follows:

45 On seizing of the repeater UA by means of a previously arranged group selector of the ex-

change A, the seizing relay $Ca1$ is energized: earth, test relay in the group selector, test wiper of the group selector (not shown), conductor c , contact $18ca2$, winding of relay $Ca1$, battery, earth. Relay $Ca1$ closes the following circuit for the relay Aa ; earth, contacts $14ca1$, $12ka$, winding II of relay Aa , battery, earth. Further by means of the relay $Ca1$ the relay Wa is energized: earth, contact $17ca1$, winding of relay Wa , battery, earth. The relay Aa connects the alternating current source $Qa1$ of 50 cycles by means of its contacts $4aa$ and $7aa$ to the transformer Tra and hence to the junction line VL . The connection of the alternating current is terminated after a short period owing to the operation of relay Ka which disconnects the relay Aa . Relay Ka is energized after the operation of relay Aa in the following circuit: earth, contacts $14ca1$, $11aa$, winding of the slow relay Ka , battery, earth. The relay Ka operates and holds over its contact $10ka$ independently of relay Aa . By the opening of contact $12ka$ the winding II of relay Aa is disconnected, relay Aa is restored, the alternating current source $Qa1$ is restored, the alternating current source $Qa1$ is disconnected from the junction line and the seizing impulse is thus terminated. The relay Wa in the repeater UA disconnects the junction line VL from the branch line extending to the group selector on its energization by the opening of contact $2wa$ and $6wa$, and by closing the contacts $1wa$ and $5wa$ switches through to the seized first group selector.

In the repeater UB the alternating current relay $Jb2$ tuned to 50 cycles is energized for a short while by means of the seizing impulse. It should be stated here that in the repeater UB the relay Eb has already been energized in a normally existing circuit previous to the seizing. This normally existing circuit extends over: earth, high resistance winding I of relay Eb , seizing conductor c , principal contact of the connected group selector (not shown), seizing relay of the group selector, battery, earth. The seizing relay of the group selector does not operate in this normal circuit. The seizing impulse for the relay $Jb2$ therefore extends over the following circuit: secondary windings of the transformer Trb , contacts $39ab$, $37wb$, $39eb$, winding of relay $Jb2$, contacts $42eb$, $34wb$, $33ab$, transformer winding Trb . Relay $Jb2$ closes the following circuit for the auxiliary relay Hb : earth, contact $46ib2$, winding of relay Hb , battery, earth. The relay Hb closes the following circuit for the seizing relay $Cb2$: earth, battery, contacts $47hb$, $54vb$, winding of relay $Cb2$, contacts $49db$, $50eb$, winding II of relay Eb , earth. The relay $Cb2$ operates in this circuit and holds after the release of relays $Jb2$ and Hb in the following circuit: earth, winding II of relay Eb , contacts $50eb$, $49db$, winding of relay $Cb2$, contacts $54cb2$, $53cb2$, battery, earth. Relay $Cb2$ seizes the second group selector not shown, of the exchange B by the direct connection of earth over contact $45cb2$ to the c -conductor. Thus in this group selector the seizing relay operates. The relay Eb , whose winding I is short circuited by contact $45cb2$ holds over its winding II in series with the seizing relay $Cb2$. Relay $Cb2$ further interrupts the incoming test conductor at contact $38cb2$ and thus prevents a seizing, by the first group selector of the exchange B , of the repeater UB in the incoming direction.

The impulses sent out from the calling subscriber are taken up by the winding I of relay

Aa on the a -conductor. The relay Aa thereby operates intermittently and transmits the impulses, by alternate closing and opening of its contacts $4aa$ and $7aa$, as an alternating current impulse directly over the junction line VL . In the repeater UB the relay $Jb2$ operates intermittently. The relay Hb energized by the relay $Jb2$ transmits the impulses as earthing impulses over the a -conductor by means of its contact $43hb$ to the second group selector and final selector. During the impulse selection the slow relay Vb is energized intermittently in the following circuit: earth, contact $52hb$, winding of relay Vb , contact $53cb2$, battery, earth. Relay Vb holds during an impulse train. Relay $Cb2$, which is short circuited intermittently over the contacts $47hb$, $49vb$ during an impulse train does not restore.

As soon as the called subscriber has replied the potential is connected to the b -conductor in the final selector as the indication for the conversation to begin and hence for the metering, by which the relay Sb is energized in the repeater UB : potential in the final selector, conductor b winding of the relay Sb , contact $42db$, earth. The relay Sb operates and by means of its contacts $51sb$ short circuits the winding II of relay Eb . Relay Eb restores and by means of its contacts $40eb$ and $41eb$ transmits an alternating current impulse back over the line VL from the alternating current source $Qb2$. The alternating current from the alternating current source $Qb2$ has a frequency of 100 cycles. The backward impulse is thus completed and after the release of the relay Eb the short circuit for the relay Db is opened at contact $50eb$. Relay Db operates in series with the relay $Cb2$ and by means of its contact $49db$ disconnects the relay Sb from the b -conductor. Relay Sb restores. Thus the short circuit for the winding II of the relay Eb is interrupted at the contact $51sb$. Relay Eb operates again. By the opening of the contacts $40eb$ and $41eb$ the alternating current source $Qb2$ is disconnected from the junction line VL and the retractive impulse marking the beginning of the conversation is completed. The contacts $39eb$ and $42eb$ again set up a connection between the junction line VL and the outgoing group selector. After the operation of the relay Eb the relay Db holds in series with the relays $Cv2$ and Eb , since the previously existing short circuit at contact $49db$ has been opened.

In the repeater UA the alternating current relay $Ja1$ which is tuned to 100 cycles is energized in the following circuit by means of the alternating current impulse from the repeater UB : windings of the transformer Tra , contacts $3aa$, $1wa$, winding of the relay $Ja1$, contacts $5wa$, $8aa$, windings of the transformer Tra . The relay $Ja1$ closes the following circuit for the auxiliary relay Ha : earth, contact $9ia1$, winding of relay Ha , battery, earth. Relay Ha closes the following circuit for the relay Ga : earth, contacts $17ca1$, $16ha$, winding of relay Ga , battery, earth. Relay Ga connects over the choke Dr and the contact $19ga$ the short period metering potential at the b -conductor, whereby in a time zone set associated with the previous group selector, the metering is stored.

When at the end of the conversation the calling subscriber hangs up his receiver the seizing relay $Ca1$ is restored in the repeater UA . On the release of the relay $Ca1$ the following circuit for the relay Aa is completed: earth, contacts $15ca1$,

13ka, winding II of relay Aa, battery, earth. Relay Aa now transmits a longer release impulse over the junction line VL by means of its contacts 4aa and 1aa. The release impulse is completed by the restoration of the slow relay Ka. The holding circuit of the relay Ka is interrupted by the opening of contact 14ca1 on the release of relay Ca1. Relay Ca1 interrupts on its release the circuit of the relay Wa as well. Relay Wa switches the junction line VL back on to the outgoing group selector.

In the repeater UB the relay Jb2 is energized by means of the long release impulse and also the relay Hb. Relay Hb energizes the relay Vb. Then over the contacts 47hb, 48vb the seizing relay Cb2 is short circuited for a long period and restores. After the release of the relay Cb2 the relays Eb and Db also restore. By the release of the relay Cb2 a seizing circuit to the outgoing group selector is opened at the contact 45cb2 and thus its release and the release of the next selector is initiated. As soon as the second group has reached its normal position the relay Eb operates over the c-conductor with its winding I. The repeaters are thus prepared for seizing again.

On a connection from exchange B to exchange A the same switching operations occur as in the previously described connection. When the repeater UB is seized over a first group selector of the exchange B by means of a calling subscriber the seizing relay Cb1 is operated over the incoming c-conductor. This effects the transmission of a short seizing impulse of 50 cycles from the alternating current source Qb1 over the junction line. Relay Cb1 thus controls a relay Ab, over a winding not shown, which with its contacts 31ab and 32ab connects alternating current to the junction line. The alternating current impulse is taken up in the repeater UA from the alternating current receiving relay Ja2 tuned to 50 cycles. Relay Ja2 energizes the seizing relay Ca2 not shown, and this seizes an outgoing second group selector by means of its contact 24ca2.

The selecting impulses from the calling subscriber are taken up from the winding of the relay Ab on the a-conductor and transmitted directly over the junction line as alternating current impulses of 50 cycles. In the repeater UA they are taken up by the relay Ja2 and transmitted as earthing impulses over the a-conductor. When the called subscriber in the exchange A replies the relay Ea is restored after a while and by means of its contacts 21ea and 22ea transmits an alternating current impulse of 100 cycles from the alternating current source Qa2 back over the junction line VL to the repeater UB. Here this is taken up from the alternating current relay Jb1 tuned to 100 cycles. Relay Jb1 switches over this impulse which marks the initiating of metering in that it connects potential at the b-conductor for a short period back to the calling subscriber. The release is performed by means of a long alternating current impulse which is transmitted from the repeater UB on the hanging up on the part of the calling subscriber.

If the repeaters UA and UB should simultaneously seize the line from opposite directions then by means of impulses in the opposite directions which for example can arise so that one of the subscribers is subsequently selected or hangs up his receiver disturbances in particular erroneous initiations of metering operations do not occur. In such a case on the one hand from the two

repeaters the junction lines are switched through to the alternating current relays Ja1 or Jb2 tuned to 100 cycles, and on the other hand the impulses transmitted from the two opposite subscribers are only transmitted with a frequency of 50 cycles whereby the alternating current relays are not operated.

Fig. 3 shows an embodiment of the invention in which all the signals, the forwardly directed as well as the revertively transmitted signals, are transmitted with the same kind of current, e. g. alternating current of the same frequency over the guarded line but have different lengths. Thus for the forwardly directed switching operations of seizing and selection short impulses are transmitted, and for the release a long impulse, while for the signal to be transmitted back for the metering a so-called half-length impulse is used. These half-length impulses are longer than the impulses for transmission and shorter than the release impulse so that when the two repeaters are connected together neither on the selection nor on the release can a metering operation occur at a subscriber's station.

The method of working of the arrangement in Fig. 3 is as follows: on the seizing of the repeater UA over a first group selector of the exchange A the seizing relay Ca1 operates over the c-conductor in the following circuit: earth, test relay in the first group selector, test wiper of the first group selector (not shown), c-conductor, contact 31ca2, winding of relay Ca1, battery, earth. Relay Ca1 closes the following circuit for the relays Ga and Aa: earth, contact 12ca1, winding I of relay Ga, contact 10na, winding II of relay Aa, battery, earth. The relays Ga and Aa operate. Relay Ga holds in the following circuit: earth, contact 5ca1, winding I of relay Ga, contact 31ga, resistance Wi, battery, earth. Further the relay Wa is energized: earth, contact 5ca1, winding of the relay Wa, battery, earth. The relay Wa connects the junction line at the contacts 23wa and 25wa through to the incoming group selector. The relay Aa transmits a short alternating current impulse of 50 cycles from the alternating current source WQa by means of its contacts 28aa and 29aa for seizing over the junction line VL. The seizing impulse is so completed that after the energization of the relay Aa the relays Ka and Na are energized. Relay Na thereupon interrupts the circuit for the relay Aa. The circuit formed for relay Ka at the energization of relay Aa is as follows: earth, contacts 12ca, 3aa, 2na, winding of relay Ka, battery, earth. Relay Ka holds independently of relays Aa and Na in the following circuit: earth, contacts 12ca1, 1ha, 4ka, winding of relay Ka, battery, earth. Relay Ka further closes the following circuit for the relay Na: earth, contacts 5ca1, 9ka, winding of relay Na, battery, earth. Relay Na interrupts the circuit for the relay Aa by opening contact 10na. Relay Na holds independently of relay Ka in the following circuit: earth, contacts 5ca1, winding of relay Na, battery, earth.

In the repeater UB the alternating current relay Jb2 is energized by means of the seizing impulses. It should be inserted here that the relay Eb has already been energized previous to the seizing of the repeater in the normal circuit extending over its high resistance winding I and the c-conductor extending to the outgoing second group selector. The relay Jb2 is thus energized by means of the seizing impulse in the following circuit: windings of the repeater Trb,

contacts 40ab, 45wb, 51eb, winding of relay Jb2, contacts 60eb, 47wb, 43ab, windings of transformer Trb. Relay Jb2 closes the following circuit for the auxiliary relay Hb: earth, contact 64b2, winding of relay Hb, battery, earth. Relay Hb closes the following circuit for the seizing relay Cb2: earth, battery, contacts 54hb, 64vb, winding of the relay Cb2, contacts 51db, 50eb, winding II of the relay Eb, earth. After the release of relay Hb the relay Cb2 holds over its contacts 56cb2 and 55cb2. Relay Cb2 interrupts the incoming test conductor at contact 48cb2 and thus prevents the seizing of the repeater UB in the incoming direction. By means of its contact 63cb2 the relay Cb2 connects direct earth to the outgoing c-conductor and thus seizes the connected second group selector whose seizing relay is now energized. The relay Eb whose winding I is short circuited by means of contact 63sb2 holds over the winding II in series with the seizing relay Cb2.

The impulses which are transmitted from the calling subscriber are taken up by the winding I of the relay Aa of the repeater UA connected to the a-conductor. Relay Aa transmits these by means of its contacts 28aa and 29aa directly as alternating current impulses over the junction line. They are taken up in the repeater UB by the relay Jb which energizes the relay Hb intermittently. Relay Hb transmits the received impulses by means of its contact 61hb as earthed impulses over the a-conductor to the succeeding selector. During the selection slow relay VB is also energized intermittently: earth, contact 52hb, winding of relay Vb, contact 56cb2, battery, earth. The relay Vb holds during an impulse train. Relay Cb2, which is short circuited during the impulse selection over the contacts 54hb, 53vb is thereby not restored.

When the required subscriber replies, potential is connected to the b-conductor in the final selector which brings about the operation of relay Sb in the repeater UB: potential in the final selector, b-conductor, winding of relay Sb, contacts 62db, earth. The relay Sb operates and short-circuits the winding II of relay Eb. Relay Eb restores and by means of its contacts 58eb and 59eb transmits an alternating current impulse from the alternating current source WQb back over the line VL to the repeater UA as a signal for the conversation to begin. Relay Eb opens the short circuit for relay Db on its release by means of contact 50eb. Relay Db operates in series with relay Cb2 and holds after the energizing of relay Eb, since the previously existing circuit at contact 51db is finally opened. Relay Db disconnects the relay Sb from the b-conductor at contact 62db. Relay Sb restores, and the short circuit for the winding II of relay Eb is interrupted at contact 48sb. Relay Eb operates. In this way the revertive impulse which constitutes the signal for initiation of metering is completed. The duration of the revertive impulse is essentially determined by the release period of the slow relay Sb. This is so arranged that the length of the revertive impulse lies between that of the short seizing impulse or selecting impulse and that of the long release impulse transmitted at the termination of the connection.

In the repeater UA by means of the half-length revertive impulse for metering the relay Ja1 is energized: winding of the relay Ja1, contacts 25wa, 30aa, windings of the transformer Tra. Relay Ja1 closes the following circuit for the relay Ha: earth, contact 11a1, winding of the

relay Ha, battery, earth. The relay Ha short circuits the winding II of relay Ga over contact 6ha. This short circuit continues for a sufficient period to bring the relay Ga to restore. The duration of this impulse is not sufficient, however, to bring the relay Ka to restore, in spite of which after the release of relay Ja the holding circuit of relay Ka is interrupted at the contacts 1ha and 1ga. Before the relay Ka has restored the holding circuit is already completed by means of the contact 1ha of the restored relay Ha. A further operation of the relay Ga after the release of the relay Ha is prevented in that the contact 31ga interrupts the energizing circuit for the relay Ga. After the release of the relays Ga and Ha metering potential is connected at the b-conductor back to the calling subscriber: earth, battery, choke, Dr, contacts 16ga, 15ha, 14ka, b-conductor back to the first group selector.

The release of the connection takes place when the calling subscriber hangs up. Thus the seizing circuit extending from the first group selector is interrupted so that the seizing relay Ca1 in the repeater is restored. After the release of the relay Ca1 the relay Aa is energized in the following circuit: earth, contacts 13ca1, 11na, winding II of relay Aa, battery, earth. The relay Aa transmits a long alternating current impulse by means of its contacts 28aa and 29aa in order to release the junction line. The duration of the release impulse is determined by the release period of the slow relay Na. Its release period amounts to about 200 ms. The holding circuit of the relay Na is interrupted after the release of relay Ca1 at contact 5ca1. Relay Na opens the energizing circuit of winding II of relay Aa at contact 11na. Relay Aa restores and thus completes the release impulse. By the restoration of relay Ca1 the holding circuit for the slow relay Ka is also opened. This relay restores but its release period is shorter than that of relay Na. The reason for this will be explained later.

In the repeater UB by means of the long release impulse the relay Jb2 is energized for a long period. Relay Jb2 energizes the relay Hb for a long period. Relay Hb energizes the relay Vb. Now over the contacts 54hb and 53vb the seizing relay Cb2 is short circuited for a long period and thus restores. After the release of the relay Hb the relays Db, Eb and Vb also restores. The relay Cb2 interrupts the seizing circuit to the outgoing group selector at contact 63cb2 and thereby initiates its release and that of the next selector. If the outgoing selector has reached its normal position the high resistance winding I of relay Eb operates over the outgoing c-conductor again and prepares the repeater UB for seizing again.

The setting up of a connection in the direction from the exchange B to the exchange A requires no further elucidation. The same switching operations occur as described previously. The repeater UB when it is seized by an incoming group selector by means of the relays Cb1 and Ab transmits a short seizing impulse from the alternating current source WQb over the junction line VL to the repeater UA. Here this is taken up by the relay Ja2 and the energizing of the seizing relay Ca2 not shown is effected.

The impulses from the calling subscriber are received by the relay Ab and transmitted as alternating current impulses over the junction VL. In the repeater UA the relay Ja2 converts the impulses to earthing impulses on the a-conductor.

When the called subscriber replies on alternating current revertive impulse is transmitted by means of the contacts 19ea and 20ea over the junction line VL to the repeater UB and here it is taken up by the relay Jb1. Relay Jb1 transmits this metering impulse back to the calling subscriber by connecting metering potential to the b-conductor.

The release takes place when the calling subscriber hangs up and is performed by the transmission of a long alternating current impulse over the junction line.

The previously described embodiment also prevents an erroneous metering being charged to one of the subscribers when the junction line is seized simultaneously from opposite directions. Thus when one of the subscribers connected to lines at opposite ends for example the subscriber of the exchange B transmits impulses after the seizing of the repeater UB the relays Ja1 and Ha are intermittently energized for brief periods by the short alternating current impulses extending from the repeater UB to the repeater UA. Over the contact 6h the relay Ga is short circuited but the short circuit does not last sufficiently long to bring the relay to restore. When the subscriber hangs up whereby a long release impulse is transmitted over the junction line from the repeater UA the relays Ja1 and Ha in the repeater UA are energized for a long period. Relay Ha short circuits the winding II of relay Ga over contact 6ha. Relay Ga restores. Further by means of the long impulse after the release of the relay Ga the holding circuit of the relay Ka is opened at contact 1ha until the relay Ka whose release period is shorter than the duration of the long release impulse, has restored. When the relays Ha and Ga restore at the end of the release impulse the metering circuit to the calling subscriber can no longer be completed since a connecting of metering potential to the b-conductor is rendered impossible by the opening of contact 14ka.

Fig. 4 shows an arrangement in which an inductive direct current impulse is provided for the signal in the direction from the calling to the called subscriber, and an alternating current impulse for the signal for metering in the opposite direction. Thus in the case of two-way traffic when the repeaters at both ends of the line are connected, no metering impulse can occur since the inductive impulse is not sufficient to operate the alternating current relay which initiates the metering.

The method of working of the arrangement in Fig. 4 is as follows: When the repeater UA is seized by a group selector of the exchange A in the incoming direction the seizing relay Ca1 operates over the test conductor of the preceding group selector: earth, test relay in the preceding group selector, test wiper of the preceding group selector, c-conductor contact 38ca2, winding of relay Ca1, battery, earth. Relay Ca1 closes the following circuit for relay Xa: earth, contacts 11ca1, 12ca1, winding of relay Xa, battery, earth. Relay Ca1 further closes the following circuit for the relay Wa: earth, contact 18ca1, winding of the relay Wa, battery, earth. Relay Wa by opening its contacts 24wa and 33wa disconnects the junction line VL from the branch extending to the outgoing group selector and by means of the contacts 23wa and 32wa switches over to the incoming group selector. Relay Xa completes the following circuit for the relay Aa: earth, contacts 11cat, 6xa, 5da, winding of the relay Aa,

battery, earth. Relay Aa completes the following direct current circuit over the winding I of the transformer Tfa: earth, contact 31aa, winding I of the transformer Tfa, battery, earth. 5 Thus in the winding II of the transformer, an impulse is induced in one direction which is marked as a positive direction. From the secondary winding of the transformer Tfa this impulse is transmitted in the following circuit to the junction line VL: winding II of the transformer Tfa, contact 28aa, primary windings of the transformer Tra, contact 30xa, winding II of the transformer Tfa. After the operation of the relay Aa the following circuit is completed for the relay Ma: earth, contact 17aa, winding of the relay Ma, battery, earth. Further after the operation of the relay Aa the following circuit is set up for the relay Da: Earth, contacts 1xa, 3aa, winding of relay Da, battery, earth. The relay Da holds over its contact 2da independently of the relay Aa. By means of the operation of the relay Da the energizing circuit for the relay Aa is interrupted at contact 5da. In this way the direct current circuit over the winding I of the transformer Tfa is first interrupted and an impulse in the negative direction induced in the winding II of the transformer Tfa which extends over contact 21ma, primary windings of the transformer Tra and contact 29ma, back to winding II of the transformer Tfa. Correspondingly an impulse in the negative direction also extends over the junction line VL.

In the repeater UB there operates the polarized accepting relay Pb due to the positive inductance impulse and the relay P closes its contact 66pb. Relay Eb has already been seized previous to the energization in the normal circuit over the seizing conductor extending to the outgoing group selector. The circuit for the relay Pb is as follows: windings of the transformer Trb, contacts 17ab, 13mb, 51wb, 63eb, winding of the polarized relay Pb, contacts 65eb, 53wb, windings of the transformer Trb. Over contact 66pb the auxiliary relay Hb is energized. By means of relay Hb the following energizing circuit is completed for the seizing relay Cb2: earth, battery, contacts 57hb, 73vb, winding of the relay Cb2, contacts 59db, 60eb, winding II of relay Eb, earth. By means of the negative induction impulse following on the positive impulse the polarized relay Pb sets back its armature for a short period. The relay Hb also restores. After the release of the relay Hb the relays Cb2 and Eb are maintained energized in the following circuit: earth, winding II of relay Eb, contacts 60eb, 59db, winding of relay Cb2, contacts 56cb2, 55cb2, battery, earth. By opening its contact 12cb2, the relay Cb2 interrupts the incoming test conductor and thus prevents a seizing of the repeater UB in the incoming direction. Further the relay Cb2 by the direct connection of the contact 67cb2 to the c-conductor seizes the outgoing group selector. Relay Eb is maintained energized after the short circuit of its high resistance winding I over the winding II in series with the seizing relay Cb2.

The impulses transmitted from the calling subscriber are received in the repeater UA by the impulse accepting relay Aa connected to the a-conductor and transmitted alternatively as positive and negative inductance impulses over the junction line VL. Relay Aa thereby closes and opens alternately a direct current circuit over the winding I of the transformer Tfa, whereby impulses in alternate directions are induced

in the winding II of this transformer. Further the relay Aa energizes the relay Ma on each impulse over contact $11aa$. Relay Ma holds over its contacts $21ma$ and $29ma$ in the impulse transmitting circuit closed during the negative impulses. 5

In the repeater UB the impulses are transmitted by the auxiliary relay Hb . The relay Hb transmits these by means of its contact $11hb$ as earth impulses over the a -conductor to the next selector while during the impulse transmission over contact $54hb$ a slow relay Vb is energized intermittently. Relay Vb holds during an impulse train. The seizing relay $Cb2$ short circuited intermittently over the contact $58cb$ and $51hb$ holds during the impulse selection. 10

When the required subscriber replies potential is connected to the b -conductor in the selector by which the relay Sb in the repeater UB is operated: potential in the final selector, b -conductor, winding of the relay Sb , contact $69db$, earth. The relay Sb operates and short circuits the winding II of the relay Eb over contact $61sb$. Relay Eb restores and by means of its contact $62eb$ and $64eb$ connects the alternating current source WQb to the junction line VL . This alternating current reverte impulse marking the metering apparatus is thus completed. After the release of the relay Ab , the short circuit at contact $60eb$ is opened and the relay Db operates in series with the relay $Cb2$. Relay Db disconnects the relay Sb from the b -conductor by the opening of the contact $69db$. Relay Sb restores. After the opening of the short circuit for the winding II of the relay Eb at contact $61sb$ the relay Eb operates again. Relay Eb opens its contacts $62eb$, $64eb$ and closes its contacts $63eb$, $65eb$, whereby the reverte impulse is completed. After the operation of the relay Eb the relay Db holds in series with the relays $Cb2$ and Eb , since the previously existing short circuit at the contact $59db$ is now finally interrupted. Relay Sb is connected in bridge across the outgoing talking conductor after the operation of the relays Eb and Db over the contacts $70eb$ and $68db$. It then serves as a monitoring relay when the called subscriber hangs up. 35

In the repeater UA by means of the reverte impulse marking the initiation of metering the alternating current relay Ja tuned to 50 cycles is energized in the following circuit: transformer windings Tra , contacts $26aa$, $25ma$, $23wa$, winding of the relay Ja , contact $32wa$, transformer windings Tra . Relay Ja completes the following circuit for relay Ha : earth, contacts $18ca1$, $1ha$, winding of the relay Ga , battery, earth. Relay Ga connects metering potential for a short period over the choke Dr and contact $19ga$ to the b -conductor which in the present case is stored in a time zone set associated with the seizing group selector. After the completion of the impulses the relays Ja , Ha , Ga again restore. 45

The release of the connection takes place when the calling subscriber hangs up. Thus the test conductor in the seizing group selector is interrupted and the relay $Ca1$ of the repeater UA is restored. After the release of the relay $Ca1$ the following circuit is completed for the relay Aa : earth, contacts $10ca1$, $4da$, winding of the relay Aa , battery, earth. Relay Aa again induces a positive impulse in the winding II of the transformer Tfa which extends over the junction line 50

VL to the repeater UB. The relay Aa only restores after a long period and thereby transmits an induction impulse of negative direction over the junction line VL . By means of the release of relay $Ca1$ the circuit for the relay Xa is interrupted at the contacts $11ca1$ and $12ca1$. The slow relay Xa at contact $11xa$ interrupts the circuit for the slow relay Da . After the release of the relay Da the energizing circuit for the relay Aa is interrupted at the contact $4da$. Relay Aa now transmits a negative inductive impulse over the junction line in connection with a long pause. The release impulse consists of a positive and negative induction impulse with a long pause. In the repeater UA by means of the release of the relay $Ca1$ the relay Wa is further brought to restore. Relay Wa switches over the connection again on to the branch leading to the outgoing group selector. 15

In the repeater UB by means of the positive inductive impulse the relay Pb is energized which operates the relay Hb . The relay Hb short circuits the relay $Cb2$ for a long period over contacts $51hb$ and $58vb$. Relay $Cb2$ restores thereby. After the release of the relay Hb the relays Db and Eb also restore. The release of the relay $Cb2$ by disconnecting the feeding potential at contact $67cb2$ from the seizing conductor initiates the release of the next selector. After the return to normal of the outgoing group selector the relay Eb operates again over the high resistance winding I and the seizing conductor c in the normal position whereby the repeater UB is prepared for seizing again. 20

What is claimed is:

1. In a telephone system, a two way two conductor trunk line, means for seizing said trunk line and automatic switches for extending connections thereover in either direction, means on each end of said trunk line responsive to impulses from a calling subscriber when the trunk line is seized for transmitting impulses of alternating current of one frequency over said trunk line to operate said switches to extend connections thereover to called subscribers, and means on each end of said trunk line operated when a called subscriber responds to the completion of a connection thereover for transmitting an impulse of alternating current of another frequency over said trunk line. 35

2. In a telephone system, a two way two conductor trunk line, automatic switches operated by a calling subscriber to seize said trunk line at either end and extend connections thereover via other automatic switches, means on each end of the trunk line responsive to seizure thereof by certain of said switches for transmitting alternating current of one frequency over the trunk line to control automatic switches thereover and responsive to impulses from the calling subscriber to transmit impulses of said frequency over the trunk line to operate the seized switches to extend a connection therefrom to a called subscriber, and means on each end of the trunk line operated when a called subscriber responds to the completion of an extended connection thereover for transmitting an impulse of alternating current of another frequency over the trunk line in the direction of the calling subscriber. 50
